UNITED STATES PATENT OFFICE.

JOHN LEIPER, OF NEW YORK MILLS, NEW YORK, ASSIGNOR TO NEW YORK MILLS CORPORATION, OF NEW YORK MILLS, NEW YORK, A CORPORATION OF NEW YORK.

DESIGN FOR A PILE FABRIC.

Application filed May 25, 1926. Serial No. 17,847. Term of patent 7 years.

To all whom it may concern:

Be it known that I, JOHN LEIPER, a citizen of the United States, and a resident of New York Mills, Oneida County, New York, have invented a new, original, and ornamental Design for Pile Fabrics, of which the following is a specification, reference being had to the accompanying drawing, forming a part thereof.

The figure is a plan view of a pile fabric showing my new design.

I claim:—

The ornamental design for a pile fabric as shown.

JOHN LEIPER.
